Patented June 4, 1918.

UNITED STATES PATENT OFFICE.

OWEN K. TRUITT, OF GARRETT PARK, MARYLAND.

PINWHEEL.

1,268,644.

Specification of Letters Patent. Patented June 4, 1918.

Application filed June 21, 1917. Serial No. 176,070.

To all whom it may concern:

Be it known that I, OWEN K. TRUITT, a citizen of the United States, residing at Garrett Park, in the county of Montgomery and

5 State of Maryland, have invented certain new and useful Improvements in Pinwheels, of which the following is a specification, reference being had therein to the accompanying drawing.

10 This invention comprises a pin wheel and a novel method of constructing the same.

It is contemplated among other objects to produce a device of this character from a blank or blanks so that when folded to the

15 proper form there will be displayed upon the face of the finished product a plurality of different colors bearing a previously defined arrangement to one another.

It is also an object of the invention to associate with the vanes of the pin wheel when properly assembled, a tie member extending from point to point in such a manner as to form an additional binding or bracing for the vanes and add to the ornamental appearance of the device.

20 A further object of the invention is to devise a method of producing an instrumentality of this character which method will eliminate some of the steps previously utilized, and at the same time produce a change in the general structure and ornamental appearance of the device itself.

25 Further objects and advantages will in part be apparent and in part be brought out in the specification which follows.

A drawing illustrating a preferred embodiment of my invention is hereto appended in which the following views are shown.

Figure 1 is a view in front elevation;

40 Figs. 2, 3, and 4 are plan views of component parts of the device.

Referring specifically to these drawings, 1 designates a face portion of a blank and 2 a back portion of a different color preferably.

45 In this instance, the face is shown as white and the back portion as blue. In the construction of a pin wheel from a blank of this type the blank is cut by diagonal lines 3 extending toward the center of the blank

50 which contains a perforation 4. The outer corners of the blank are also provided with perforations or openings 5, which are adapted to be folded inwardly to bring the perforations 5 into alinement with the opening

55 4 in the center of the blank, as best seen in Fig. 1. Before the corners have been folded

into this position, the blank 6 having a central perforation 7 is placed upon the blank 1 so that the central perforation 7 of the blank 6 will register with perforation 4 in blank 1. 60 When in this position, the corners of the blank 1 are folded over so that their perforations 5 register one with another whereupon a fastening element 8 is inserted securing them together and a pin or the like 65 9 is passed through the alined openings and suitably secured to a handle or the like 10.

The pointed ends of the vanes left free after this folding operation are provided with perforations or openings 11 through 70 which there is adapted to be passed an additional bracing or securing means 12 in the form of a ribbon and which may likewise be of a color and arrangement which will lend itself suitable to the decorative appearance 75 of the device. In like manner a ribbon 13 may be entwined in and out among the folded portions in the center of the device to form an additional securing means therefor and add to its attractive appearance. 80

In practice, and as herein illustrated, the face portion of the blank is white, the back portion thereof is shown as blue and the insert-blank is red. When the back portion has been folded over and secured as shown 85 in Fig. 1 the effect is to present to the eye an arrangement of colors wherein red, white and blue predominate in the color scheme and present a very attractive appearance. This may be aided by the interlacing of the 90 additional bracing members 12 and 13, the combination forming a neat and attractive device of this kind which is easy to manufacture and has a minimum number of parts.

It will be understood that this same effect 95 can be produced by using two separate blanks one to form the face portion and one to constitute the back portion of the device, each blank being of a different color, or this same effect may be produced by a single 100 blank having on its face portion one color and a back portion of a different color, and the present disclosure is intended to embody these two forms.

It will be also understood that while the 105 insert-blank 6 is herein disclosed as square, yet I do not wish to confine myself to this particular shape as it may be with equal facility made round, diamond or star shaped, or in fact any shape that would lend itself 110 to additional ornamentation, as occasion may demand.

While I have disclosed the invention in the embodiment herein set forth, it will be understood that I do not wish to limit myself to the precise form of this disclosure as many changes in the structure and arrangement of the parts may be made without departing from the spirit of the invention or sacrificing its chief advantages.

What I claim is:

- 10 1. A pin wheel comprising a face element; a back element foldable from the outer edges inwardly over the face element; means for securing the folded portions of the back-element together at a point intermediate the outer edges of the face-element; and a blank disposed upon the face-element and embraced by the folded portions of the back-element when they are secured together.
- 20 2. As an article of manufacture, a pin wheel or the like comprising a face portion of one color; a back portion of a different color; said portions being cut from their corners toward their center and provided centrally and on the corners with openings 45 adapted to be brought into register; said corners being folded over, perforations therein being in alinement with the opening of the center of the portions; a handle member; means for securing the corners with 50 their perforations in approximate alinement to said handle member whereby the color of 55

the back portion will be imposed upon the color of the face portion; and a blank provided with a perforation disposed upon said face portion and embraced by said corners when folded into position and secured to said handle.

3. As an article of manufacture, a pin wheel or the like comprising a face portion of one color; a back portion of a different color; said portions being cut from their corners toward their center and provided centrally and on the corners with openings 40 adapted to be brought into register; certain of said corners being folded over, the free outer corners forming vanes, perforations 45 therein being in alinement with the opening of the center of the portions; a handle member; means for securing the corner members with their perforations in alinement to said 50 handle member whereby the color of the back portion will be imposed upon the color of the face portion; and a bracing member secured to the free outer edges of each vane and connecting the vanes one with the other. 55

In testimony whereof I affix my signature in presence of two witnesses.

OWEN K. TRUITT.
